(57) **CLAIM**

The ornamental design for a passive sampler for environmental water monitoring as shown and described.

DESCRIPTION

FIG. 1 is the front view.

FIGS. 2 and 3 are the left and right side views, respectively.

FIGS. 4 and 5 are the top and bottom views, respectively;

and,

FIG. 6 is the rear view.

In FIG. 1, the central mesh is framed. In FIGS. 2 and 3, the left and right side views show only the frame is visible. In FIGS. 4 and 5, the top and bottom views show only the frame is visible. In FIG. 6, the central mesh is framed, with the frame being extended in some shape.

The broken lines represent portions of a passive sampler for environmental water monitoring and form no part of the claimed design.

1 Claim, 4 Drawing Sheets
